Miller, Henry & Boykin

ATTORNEY.

UNITED STATES PATENT OFFICE.

ROY A. BADT, OF LOS ANGELES, CALIFORNIA.

MEANS EMPLOYED IN REINFORCED CONCRETE CONSTRUCTION.

Application filed November 22, 1923. Serial No. 676,259.

To all whom it may concern:

Be it known that I, ROY A. BADT, a citizen of the United States, and a resident of Los Angeles, county of Los Angeles, State of California, have invented new and useful Improvements in Means Employed in Reinforced Concrete Construction, of which the following is a specification.

My invention has for its object forms, and supporting elements for forms, employed in determining the limiting surfaces of concrete or plastic material to be molded therein.

A further object is the supporting means for said forms, which means are provided to extend within the mold and be partly imbedded within the molded plastic material, to form a tie or angle member for other structure subsequently suspended therefrom.

A further object is a tie to be employed in reinforced concrete mold forms whereby the forms are positioned and spaced in accordance with predetermined measurements and which tie extends into the mold form and has an end divided or shaped to receive and to hold in spaced relation within the mold, a reinforced bar or bars.

A further object is the provision of metal plates to form mold surfaces for reinforced concrete, in combination with adjustable supporting means therefor, whereby the plate is held in predetermined spaced relation with other portions of the mold forms.

Other objects will appear from the drawings and specifications herewith attached.

These objects I attain by positioning on suitable supports, straps or strap members, which are bent in the form of a **U** at their lower portions for holding portions of the forms. A plurality of these straps are arranged with bent **U** portions in line with each other and the plate, which is to form a portion of the mold surface then rests in this series **U** ends. The other end of the straps extend beyond and are preferably bent upward from their attachment to the support, and the upward extending end is bifurcated to form a cradle in which the reinforcing bars are positioned prior to their being imbedded in the concrete. One of the bifurcated ends in floor beam structures and the like extends from and rests against, and is therefore supported by, an adjacent plate member.

By referring to the accompanying drawings, my invention will be made clear.

Figure 1 is a section and part perspective of two of my plates positioned in a plurality of straps of simplest form, the said two plates forming portions of the mold surface for forming a floor beam of reinforced concrete.

Figure 2 is similar to Figure 1, except that one of the plates has been removed and the concrete has been molded therein, and the straps here shown are of somewhat different construction.

Figure 3 is similar to Figure 2 except that both plates have been removed and the straps which remain imbedded in the concrete have now been bent down and are further employed to hold a portion of the roof structure for the floor below.

Figure 4 is a perspective view of the strap employed in Figures 2 and 3.

Figure 5 is a detail of the strap of Figure 3 in combination with a wire loop whereby the loop and therefore the strap supports the roof structure.

Throughout the figures similar numerals refer to identical parts.

A plate adapted to form a portion of the mold surface is shown by the numeral 1, and a similar portion of another similar plate is shown by the numeral 2. Between these there is a supporting beam 3 for carrying the mold forms, two plates with the beam being adapted to form the reinforced concrete beam 4, which is a truss for the floor 5. At 6, 20, 23 and 7 are reinforcing steel bars to be molded into the plastic material between the forms.

In the form shown in Fig. 1 the strap 8 extends across the top of the beam 3, being of a general inverted **U** shape with smaller **U** ends turned out on each side. A plurality of these are spaced as desired on the beam 3, as shown also at 12, 13, whereby the plate 2 on the one side and the plate 1 on the opposite side of the beam 3, are adequately held in proper positions.

In Fig. 2 the straps are of somewhat different shape, having a single side 14, a bent-up end 15, a top member 16 and a single end 17 extending to contact against the plate at 18, and having a turned back portion 19 adapted to cradle the reinforcing bar 20. This strap is used by spiking the part 16 thru the hole 23 to the supporting beam 3, 110

A plurality of these straps are positioned as shown at 14, 21, of Fig. 2, by nailing them as shown at 23 to the support 3, in their proper spaced relation.

5 The arm ends 17, 19 of the several straps then form a series of cradles into which the reenforcing bar 20 rests. The bar 23 rests in a similar series of supporting cradles on the opposite end on straps as 24, adapted to 10 hold also the plate 25 from their depending **U** ends. As shown in this drawing, the plate which rested in the straps 14, 21, has been removed from the surface of the molded concrete 26, which is therefore now exposed, 15 leaving the straps in plain view.

When the beam 3 is removed from the molded concrete, the straps remain in position therein and may now be bent down to any desired angle as shown in Figure 3, and 20 the ends as bent or rebent in any way desired may be employed to carry channels as 27, 28, from which channels the conventional ceiling structure 29 may be supported for the story below.

25 If preferred a wire-loop may be made thru any of the holes 30, 31, 32, as shown at 33, and the ceiling structure 34 may be suspended therefrom, thus enabling the ceiling to be positioned as may be required without 30 reference to the original length of the straps, see Fig. 6.

I claim:

1. A mold form for concrete comprising a right plate and a left plate, a supporting truss and a plurality of metallic members fixed on the top of said truss and bent alter-

nately right and left thereover, the depending ends of said members bent upward and supporting the lower edges of said plates and the upper ends of said members bent 40 at an angle and within the mold and bifurcated to support reenforcing means.

2. A mold form for concrete comprising a right plate and a left plate, a supporting truss and a plurality of metallic members 45 fixed on the top of said truss and bent alternately right and left thereover, the depending ends of said members bent upward and supporting the lower edges of said plates and the upper ends of said members bent at 50 an angle and within the mold and bifurcated to support reenforcing means, one of the bifurcated terminals resting against one of the plates.

3. A mold form for concrete comprising a right plate and a left plate, a supporting truss and a plurality of metallic members fixed on the top of said truss and bent alternately right and left thereover, the depending ends of said members bent upward 55 and supporting the lower edges of said plates and the upper ends of said members bent at an angle and within the mold and bifurcated to support reenforcing means, one of the bifurcated terminals resting against 60 one of the plates and said members between the ends having openings to fasten to the truss and holes to engage wires adapted to 65 suspend additional structure therefrom when the concrete has set about the bifurcated ends.

ROY A. BADT.
